UNITED STATES PATENT OFFICE.

REINHARD E. BARTELS, OF LYNN, MASSACHUSETTS.

APPARATUS FOR LOCATING SHANK STIFFENERS IN SHOE SOLES.

Original application filed April 26, 1920, Serial No. 376,633. Divided and this application filed May 17, 1922. Serial No. 561,592.

To all whom it may concern:

Be it known that I, REINHARD E. BARTELS, a citizen of the United States, residing at Lynn, in the county of Essex and State 5 of Massachusetts, have invented new and useful Improvements in Apparatus for Locating Shank Stiffeners in Shoe Soles, of which the following is a specification.

In attaching rigid shank stiffeners to shoe 10 soles, the forward end of the shank stiffener should be located a short distance back of or "below" the break line in order that the resiliency of the shoe at the break line may not be impaired and the shoe thereby ruined.

The shank stiffener is attached to the shank of the sole while the sole is flat and before it has been shaped to its final form, and for this reason it is difficult to judge when locating the stiffener, where the break 20 line will be on the sole when the shoe is completed. Consequently, many soles have been spoiled by the location of the shank stiffener too far forward or too far back relative to the break line, in the first instance, destroying 25 the resiliency of the sole at the break line, and in the second, throwing off the tread of the heel, either of which faults is undesirable from the standpoint of good 30 workmanship, if not fatal to the usefulness of the shoe.

One object of my invention is to overcome these difficulties by producing a gaging apparatus, whereby the workman can quickly and accurately locate the shank stiffener on 35 a sole of a given style and size.

Another object of my invention is to provide means whereby when the desired point for the end of the shank stiffener on a sole of one size of a certain style has been located, the corresponding point for any other 40 size of that same style may be readily located.

A still further object is to produce mechanical means whereby the desired point in 45 any given sole may be readily and accurately located.

A specific embodiment of my invention by which the above objects may be accomplished is illustrated on the accompanying drawings, the subject matter of this application being divided out from my application Serial No. 376,633, filed April 26, 1920, for apparatus for locating shank stiffeners in shoe soles. Referring to these drawings, 50

Figure 1 is a plan view of the apparatus with a shank stiffener in place thereon, the

position of the sole for the attachment of the stiffener thereto being shown in dotted lines.

Figure 2 is a fragmentary section on line 60 2-2 of Figure 1.

Figure 3 is a perspective of the shank stiffener.

My apparatus may be used to locate any desired point on the sole of a shoe, but the particular use for which it is designed is to locate a point on the shank of a sole of given style and size at which the forward end of a shank stiffener, to be attached thereto, should terminate. In actual practice, this point is located on the sole about 65 one-fourth of an inch back of the break line.

The arcuate location of this point by mechanical means is made possible by the fact that the forepart of the sole, i. e., from the toe to the break line, varies in length by approximately one-sixth of an inch for each change of full size of the shoe, regardless of style. Therefore, if a point is selected on the sole of a shoe of any known style and size, called for convenience the "selected sole", and it is desired to locate the corresponding point on a sole of a different size of the same style, called for convenience the "problem sole", one proceeds as follows: First, the distance from the toe to the break line is measured on the "selected sole", and then the distance from the break line to the point selected is added to or subtracted from this distance, according as the point lies behind or in front of the break line. Then one-sixth of an inch for each unit of size number by which the "problem sole" is 70 greater than, or less than the size of the "selected sole", is added to or subtracted from the distance found above, as the case may be. This new distance will be the distance measured rearwardly from the toe at 75 which the required point lies on the "problem sole".

Slidably arranged on the forward end of a plate 10 is a gage or locating plate 17, the side edges 19 of which are beveled outwardly to fit slidably in the complementary undercut 80 inner edge of guideways 20 and 21. These guideways may be formed integral with the plate 10, or, as shown, may be attached thereto by means of screws and extend from the forward end thereof, rearwardly along 85 the edges for about half the length of the plate. The slide 17 is provided with a 90

curved recess 18 in the edge thereof toward the rear of the plate 10. This recess may be of such contour and size as to receive the toe of a sole of practically any style or size 5 which may be placed on the plate.

The locating plate may have a scale 22 cut on one of the side edges thereof, corresponding to the styles of shoes, say, from 1 to 16 inclusive, and the complementary guide 10 member has a similar scale 23 on its inner edge adjacent to the graded side edge of the location plate. The gradations of the scale on the guide member are so spaced that each full gradation is equal to the difference 15 of length between the sole of one size of shoe and the next larger size, as stated above, one-sixth of an inch. Half grades, or half sizes, or any other fractional sizes may be indicated on this scale. The gradations of the 20 scale 22 on the locating plate are arbitrary, and there may be as many to the inch as is found convenient; the only requisite is that they be sufficient in number, so that one of the gradations on the slide may come approximately opposite a gradation on the 25 guide member, corresponding to the size of the shoe sole when a key number on the slide is being found. The scale which indicates size may be called the size scale, and 30 the full grades thereof, size numbers or size grades.

Located on the guide member 21 is a clamping member adapted to clamp the locating plate 17 in adjusted position. This 35 clamping member comprises a washer 24 resting on the guide members 21, and a bolt 25 passing through the center thereof and screw threaded into the guide member 21 and plate 10. This bolt is provided with a 40 head 26 adapted to bear on the upper surface of the washer to cause it to clamp the slide in position. The head of the bolt may be turned to and from clamping position by means of the lever arm 27 extending therefrom.

A recess 90 is formed lengthwise in the plate of such size and dimensions that a shank support may be placed therein, with the tines extending upwardly. A suitable 50 guide member 93 may be used in order to properly position the sole on the plate so that the shank stiffener will be positioned with its longitudinal central line lying directly beneath the longitudinal central line of the sole. The guide is provided with means at 55 95 whereby it may be adjusted for each size and style of sole placed on the plate.

The particular gradation of the locating plate 17, which comes opposite a gradation 60 on the guide member for any given size, varies with the style of the shoe. In order to find this gradation for a given style, I first select a last of a known size of the style in question, and measure the length of the 65 forepart of the last, i. e., from the toe to

the break line, and add to this, one-eighth to one-quarter of an inch for the overhang of the sole, that is, the distance that the sole extends beyond the last after the upper is pulled over the last; and one-quarter of an 70 inch for the distance back of the break line at which the forward end of the shank stiffener is preferably to be located. I then mark off this distance forwardly along the plate 10 from the forward end of the recess 75 90 and set the location plate so that the apex of the curve or recess is located at the forward end of the measured line, and clamp the locating plate in this position. The gradation on the locating plate which falls 80 opposite the size number on the guideway 20, corresponding to the size number of the last selected, is marked as at X to form the reference line, and is taken to be the key number for the given style. Thus in Fig. 85 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 labor, and the output is very much increased. The cost of production is correspondingly diminished.

Having thus described an embodiment of this invention it will be evident to those skilled in the art that many changes and modifications might be made therein without departing from its spirit or scope as defined by the appended claims.

19 I claim:

1. A device for locating a shank stiffener with its forward end at a desired point on a shoe sole, comprising a plate on which the sole is placed, said plate having a recess adapted to receive the shank stiffener, and an adjustable slide on said plate, whereby when the slide is adjusted for a given size and style of sole, and the toe of the sole of said size and style abuts thereagainst, the point will lie at the forward end of said recess.

2. A device for locating a shank stiffener in a desired position on a sole, comprising a support, means for holding the shank stiffener definitely positioned on the support, and abutments on the plate against which the sole may be placed so as to position the sole above the shank stiffener in position to be attached thereto in the desired position.

3. A device for positioning a sole and shank stiffener, relative to each other so that the shank stiffener may be attached

to the sole in a desired position thereon, comprising a plate having means thereon 35 for holding the shank stiffener in a fixed position, and abutment members on said plate adapted to be adjusted to position a sole above said shank stiffener in the desired position relative thereto.

4. A device for positioning a sole member and shank stiffener member relative to each other so that the shank stiffener may be attached to the sole in a desired position thereon, comprising a plate having means 45 thereon for holding one of said members in a fixed position, and abutments on said plate adapted to be adjusted to position the other of said members above said fixed member in the desired position relative thereto. 50

5. A device for locating a shank stiffener with its forward end in a desired position on a shoe sole, which comprises a plate having a recess in its upper face to receive a shank stiffener with sole-attaching elements 55 thereon upwardly extended, and a gage slideable on said plate against which one end of a sole supported on said plate may engage to correctly position it over said shank support, whereby on striking blows over said 60 attaching elements, said shank stiffener is attached to the sole in correct position.

In testimony whereof I have affixed my signature.

REINHARD E. BARTELS.
